UNITED STATES PATENT OFFICE

1,931,218

BEARING

Alfred Alsaker, Chicago, Ill., assignor to The Delta-Star Electric Company, Chicago, Ill., a corporation of Illinois

Application April 30, 1930. Serial No. 448,511

7 Claims. (Cl. 308—189)

This invention relates in general to electrical mechanism, and more particularly to rotary switches, the invention being particularly concerned with the construction of the bearing for the rotary insulator of disconnect switches.

A disconnect switch normally is opened only when a piece of apparatus or a line is taken out of service. Hence it may stand in its closed position for a relatively long period of time. In recent times there has been a rapid increase in transmission voltages and as a result thereof the insulation and striking distance dimensions have been compelled to keep pace therewith. Obviously, the greater the length of the insulator and the blade, the greater is the necessity for accuracy in the fit of the moving parts. This is particularly true of the bearing for the rotary insulator in a rotary switch, since any play or looseness in such bearing would result in failure 20 of the blade to keep its alignment with the switch contacts.

Another element to be taken into consideration in connection with outdoor switches is sleet, i. e., ice frozen upon the switch. It is evident that the larger the switch blade, the greater is the resistance offered to opening of the blade when covered with sleet. Similarly, the resistance to closing is increased by the length of the blade.

In order to provide a switch operable in all kinds of weather and at any time without fail, various forms of the so called "opening movement" have been devised. In general these forms comprise a mechanism for exerting a push or pull upon the switch blade during the initial rotation 35 of the rotary insulator stack. Such movements generally provide a change of direction of movement of the switch blade by a mechanism capable of exerting great force upon the blade to break it loose from the contact when it is held by sleet or corrosion, or merely the friction of the grip 40 of the stationary contact.

In rotary switches employing the above type of movement, the rotary insulator is put under considerable stress. The bearing will, in operation, tend to become loosened. Attempts have heretofore been made to obviate the above difficulty by the use of a relatively large close fitting bearing. This bearing, however, does not solve the problem because corrosion and sleet will 45 freeze such a bearing so tight that it cannot be operated or moved.

A plain cylindrical bearing which has a sufficiently tight fit to give the desired guiding action to a long blade or the like, of necessity presents 50 such an extensive capillary area between the cy-

lindrical surfaces of the moving part and its stationary bearing part, that if moisture or corrosion become lodged in the same the two parts will be so firmly frozen together that the switch cannot be opened. This, of course, is fatal to switch 60 operation.

I have solved the difficulty by the provision of a ball bearing support for the insulator. I wish to call attention to the fact that I employ the ball bearing not so much in its capacity to stand 65 high speeds and continuous operation with low friction as I do to provide a relatively accurately aligned bearing which cannot be frozen or corroded fast. If the bearing does corrode or fill with sleet, the balls will cut their way through 70 the same.

This is because the bearing is substantially free of any capillary recesses in which moisture could be drawn in and frozen or in which corrosion could lock the parts together. The balls 75 which are employed in the bearing have substantially only point contact with their cooperating surfaces, and furthermore they present a leverage to break away any film of moisture or corrosion which may freeze the parts together. This employment of ball bearings to eliminate freezing due either to ice or corrosion, is fundamentally new in the art.

In the manufacture of my bearing, I do not harden and grind the races for the balls as the 85 service which is required of the bearing is of such a character that a fine surface would be wasted. I depend primarily upon the balls to deform the races to such an extent as to furnish the finish or fit desirable or necessary between 90 the balls and the races. Also, if any corrosion or freezing does occur, the balls can cut their way through and, in extreme cases stretch or strain the metal of the races without cracking of the 95 balls.

My bearing comprises an outer barrel or shell member into which extends a spindle member. The shell is provided with a flange for mounting the same and the spindle is provided with a relatively flat head adapted to receive an insulator 100 pin or the like, which is rigidly secured thereto and which has an insulator secured to its opposite end in the usual manner. Both the shell and the spindle are formed of cast iron although other metals may be used if desirable. The cast 105 metal is necessarily relatively soft and affords a relatively coarse finish. On large and on medium size switches the weight of the moving mass is quite considerable and I have found that soft metal castings are not quite satisfactory unless 110

means is provided for preventing too great a give of the metal at the races. To overcome this difficulty I provide at least one of the race surfaces with a comparatively hard metal disc which comprises a race, said disc being backed up by the casting. In the very large sizes of switches or in switches of intermediate sizes wherein the rotating insulator is mounted in a cantilever position I prefer to provide all of the races with hard metal discs which will constitute hard metal races backed up by the softer casting material. I have found by actual test that the balls that are placed between the races wear into the races somewhat, but this action soon reaches equilibrium due to the hardening action of the rolling contact.

In order to prevent the entrance of moisture between the bearing surfaces I provide the spindle with an overhanging eave adjacent the upper bearing. This eave is a part of the hard metal disc that constitutes one of the race members. This disc extends outwardly from the body of the spindle and overlies the shell or barrel member and is provided with a divergent portion which constitutes a water shed for preventing the entrance of water, sleet, or the like into the bearing.

Other objects and advantages of the present invention will more fully appear from the following detailed description taken in connection with the accompanying drawings which illustrate two preferred embodiments thereof.

In the drawings:

Figure 1 is a side view in partial section showing my improved insulator supporting means;

Figure 2 is a sectional view taken along the line 2—2 of Figure 1;

Figure 3 is a view corresponding to Figure 1 and showing a somewhat modified form of insulator supporting bearing; and

Figure 4 is a sectional view taken along the line 4—4 of Figure 3 and looking in the direction of the arrows.

Reference may now be had more particularly to Figures 1 and 2 of the drawings. These figures show a bearing adapted to support the rotary insulator of a high voltage disconnect switch. An insulator unit of a standard construction is adapted to be mounted upon the rotary member of the bearing. I have shown the end portion of an insulator pin 10 which is secured to the insulator in a manner well known in the art. The lower end of the insulator pin 10 has a flat surface 12 which is adapted to seat on top of a hollow cast metal supporting element or spindle 13. The spindle member 13 is preferably a hollow casting of malleable iron or bronze. At the junction of the head at the spindle there is located a bearing 14 which will be more fully described as the description proceeds. The spindle member 13 is hollow and a bolt 16 extends through the bore 15 thereof. The bolt 16 is threaded at its upper end as indicated at 17 and is threaded into a drilled and tapped opening in the bottom of the insulator pin 10. The lower end of the bolt is provided with a square head 18 which bears against a plate 19 at the bottom of the spindle 13.

A plurality of holes are formed in the flat surface 12 of the insulator pin 10, said holes registering with correspondingly spaced holes in the top of the head of the spindle 13. Dowel pins 20 fit into the holes and extend between the insulator pin and the spindle 13 thereby preventing relative rotation between those two parts. These pins also serve to align the insulator pin with the

spindle so as to obtain a proper alignment of the switch blade, which is mounted on top of the insulator, with respect to the spindle member. The bolt 16 in connection with the plate 19 serves to rigidly secure the insulator pin 10 to the spindle.

Surrounding the spindle 13 and substantially concentric therewith is a malleable or bronze barrel 25 having an upper conical bearing base 35 which constitutes a ball race and which is located immediately below the race 14. The barrel or shell member 25 is provided with laterally projecting flanges 26—26 which are adapted to rest on the top of a fixed support 27. The support 27 may comprise any suitable channel shaped member or may be of any other preferred shape. The support 27 has a central aperture 28 therein and through which the body of the supporting shell or barrel 25 extends. The annular flanges 26 may be fastened to the top of the channel support 27 by any suitable means, such, for example, as bolts and nuts 30.

In addition to the annular radial shoulder 14 the spindle 13 is provided with an axial load bearing surface 35'. A stainless steel disk or washer 36 lies against the radial bearing surface 14. This disk or washer may be approximately one-eighth of an inch thick although it is to be understood that I am not limited to this dimension. The disk 36 extends beyond the body of the spindle 13 and is provided with a downwardly divergent portion 37 which overhangs the top portion 38 of the barrel or shell 25 and acts as a water shed for preventing the entrance of moisture or the like into the space between the shell 25 and the spindle 13. It is to be noted that the portion 37 of the washer is spaced from the shell 25 by a considerable amount. The bearing is thus free of capillary spaces at this point, thereby avoiding any possibility of the parts becoming frozen or corroded together due to moisture creeping up the barrel member by capillary action. Stainless steel balls 40 are interposed between the washer 36 and the upper conical race 35 of the barrel member. It may thus be seen that the washer 36 constitutes a hard metal ball race and that the balls 40 ride between the conical race 35, the axial race surface 35', and the race 36.

Adjacent its lower end the spindle is provided with an axial load surface 45 which cooperates with a conical race 46 formed at the lower end of the barrel or shell member 25. The spindle is threaded externally adjacent its lower end as indicated at 47 and a castellated nut 49 is threaded thereon. A stainless steel ring or washer 51 of an inner diameter sufficient to clear the threads 47, rests upon the nut 49 and constitutes a lower race for the bearing. Stainless steel balls 52 are interposed between the race 46 and the race 51. The nut 49 is then drawn up with the required degree of tightness thereby adjusting the spindle within the barrel member. The nut is then secured against becoming loose by means of a pin or the like indicated at 55 which passes through one of the notches 56 in the castellated nuts through a hole provided for that purpose in the spindle member.

The conical race surfaces 35 and 46 of the barrel 25 as well as the axial race surfaces 35' and 45 of the spindle are preferably machined to remove the rough surfaces present in the casting. The extent of this machining is however very slight so that these races do not present machine finished surfaces to the balls. These

surfaces are relatively soft and I depend primarily upon the balls to finish or fit the surfaces. As previously stated, the balls wear into the races somewhat and soon reach an equilibrium depth.

5 The head portion 21 of the spindle is provided with an upper flange 60 and a lower flange 61. Between the upper and the lower flange the spindle is provided with flat clamping surfaces 63 to which a clamp 64 may be attached for turning the spindle and thereby actuating the switch controlled by the insulator pin 10. This clamp may be of any approved construction although I prefer to use a clamp of the type shown in the pending application of myself and Elias G. Corneliusen, Serial No. 378,337, filed July 15, 1929. The clamping face 63 is of a polygonal shape, preferably octagonal, although any other number of sides may be provided if desired. The flanges 60 and 61 prevent displacement of the 20 clamp along the spindle. The spindle is provided with a similar octagonal clamping surface 66 adjacent its lower end for receiving a clamp similar to the clamp that is mounted at the other end of the spindle. This bottom portion of the 25 spindle is likewise provided with flanges 67 and 68 for preventing the displacement of the lower clamp.

It frequently happens that switches are mounted in an under-hung position. Under such 30 condition the position of the bearing shown in Figure 1 would be inverted. When the switch is mounted in this position I reverse the locations of the washers 36 and 51. The washer 36 will now provide an overhanging eave at 37 for the portion 70 of the barrel 25, which portion is now in the upper position. No other changes need be made in the bearing when changing from an under-hung to an upright type of switch or vice versa.

40 The barrel 25 is provided with a plugged hole indicated at 70' whereby the space 71 between the barrel and the spindle may be filled with a lubricating grease if desired. I have found, however, that a filling of grease is not necessary 45 in most cases and grease cups are therefore not provided. Both the barrel or shell member 25 and the spindle member 13 are hot galvanized after machining so that rusting of the machined surfaces is prevented.

50 On heavier types of switches, or on switches that are mounted so that the bearing member extends horizontally or at an angle to the vertical whereby cantilever stresses are present I prefer to provide hard metal races on the barrel or shell 55 member as well as on the spindle member. Such a bearing is shown in Figures 3 and 4. In this form of bearing there is shown an insulator pin of the type provided with a base flange 12 that is provided with a number of spaced holes for receiving bolts and nuts 75 for mounting the same. The head of the spindle 13 is therefore provided with a similar flange 76 having similarly spaced holes for receiving the shanks of the bolts 75 whereby the insulator pin may be 60 rigidly bolted to the spindle. This bearing is substantially identical to the bearing previously described, differing therefrom mainly in that I have here provided the conical race surfaces of the barrel or shell member 25 with stainless steel 65 conical races 78 and 79. These races may be approximately one-eighth of an inch thick although I do not wish to be limited to this dimension. The upper race 36' of the shell is provided with an axial bearing surface 80 as well as 70 with the radial bearing surface and in a like

manner the race or washer 85 that is carried by the nut 49 is provided with an axial bearing surface as well as with a radial bearing surface. If the switch supported by the bearing shown in Figures 3 and 4 is to be mounted in an under-hung position then the washers or races 85 and 36' are interchanged.

80 In this construction the barrel or shell member 25 is provided with a substantially square flange 26' which is provided with four bolt holes and which rests upon the web of the channel supporting frame 27. It is of course to be understood that any other form of flange may be used and that the same may be mounted other than upon a channel frame. In other respects this bearing member is identical to the bearing shown in Figures 1 and 2 and a further description thereof at this time is not deemed to be necessary to a full understanding of the invention. It might suffice to state, for the present, that the conical races 78 and 79 of Figure 3 may be provided for a bearing of the type shown in Figure 1, or that the bearing of Figure 3 may be arranged to receive an insulator pin of the type shown in Figure 1, in which case a bolt such as 100 16 would be provided.

90 In accordance with my invention the hard metal disk races may or may not be used for the conical surfaces but they will be used on the flat surfaces in all cases. The balls used are of 95 stainless steel and are a good deal harder than are the races. Should the balls become corroded to the races they can break their way through the corrosion even to the extent of deforming the races if necessary. If the balls should 105 encounter obstruction from scale, ice or other causes the pressure of the ball against the race would still be great enough to deform the hardened races and if necessary to deform the soft metal back of the races rather than crack the 110 balls.

115 In compliance with the requirement of the patent statutes I have herein shown and described a preferred form of my invention. It is however to be understood that the invention is 120 not limited to the precise construction shown herein, the same being merely illustrative of the invention. What I consider new and desire to secure by Letters Patent is:

1. A non-freezing bearing adapted to stand 125 exposed to the weather and comprising a substantially vertically extending hollow spindle having an enlarged head portion integral therewith at one end, a thin metal ball race adjacent the junction of said head and spindle, said 130 ball race having a portion extending outside of the spindle and constituting a water shed for preventing the entrance of moisture into the bearing, and a supporting barrel having a co-operating ball race disposed under said water 135 shed and supporting said spindle, there being a substantial clearance between said thin metal race and barrel to prevent the two surfaces being frozen together.

2. A non-freezing bearing for outdoor service 140 comprising a hollow cast metal spindle having an enlarged head portion at one end, a ball race comprising a thin hard metal disk adjacent the junction of the head and spindle, said disk having an overhanging eave providing a water shed 145 for preventing the entrance of moisture into the bearing member, a barrel having a co-operating ball race disposed under said water shed, balls in said races, said spindle having a formation to provide an attachment for a split clamp, 150

and means at said formation to prevent displacement of the split clamp.

3. In combination, a channel having an aperture through its web, a cast metal barrel member mounted in said aperture and having a clamping flange formed integrally therewith and lying against the web of the channel, a cast metal spindle having ball races at each end, the upper ball race comprising a thin metal washer extending beyond the body of the spindle and having a short divergent flange forming an eave overhanging the upper ball race, said barrel having cooperating ball races, and balls in said races.

4. A vertical non-freezing bearing comprising a relatively short vertically extending open ended hollow shell having ball races formed thereon at its upper and lower ends, means for mounting the shell on a stationary supporting structure, a cast metal spindle extending vertically into the shell having an enlarged head with a flat clamping surface at the top, a ball race comprising a relatively thin hard metal washer secured to said spindle and extending beyond the same to form a divergent eave portion, said ball race overlying the upper ball race of the shell, balls between said two last mentioned races, an adjustable nut for the lower end of the spindle, and a relatively thin hard metal disk constituting a ball race and movable by said nut towards and away from the lower ball race of said hollow shell, and balls between said two last mentioned races.

5. A non-freezing infrequently operated bearing adapted to be mounted outdoors and exposed to weather, said bearing comprising a cast metal spindle and an outer cast metal barrel into which the spindle extends, there being a considerable spacing between the two to prevent the parts becoming corroded together, cooperating bearing races formed on said spindle and said barrel adjacent the opposite ends of the barrel member, hardened balls in said races, one of said bearing members having a thin hard metal facing comprising a disc which extends beyond the barrel member and constitutes a water shed for preventing the entrance of moisture into the barrel, said facing being of a thinness to permit a deformation of its cast metal backing before the cracking

of the balls takes place in the event of an attempted operation while the balls are frozen to the facing metal.

6. A non-freezing infrequently operated rocking bearing adapted to be mounted outdoors and exposed to weather, said bearing comprising a cast metal spindle and a vertically extending outer cast metal barrel into which the spindle extends and in which the spindle is journaled, there being considerable spacing between the barrel and the spindle to prevent those parts becoming corroded together, said barrel member having relatively soft races formed integrally therewith, said spindle member having a ball race formed at one end thereof and having an adjustable ball race threaded on to the other end, said two last mentioned races cooperating with the races on the barrel and the upper one of the two last mentioned races comprising a thin hard metal disk having a portion extending outwardly from the spindle and forming an overhanging eave for the upper race of the barrel to prevent entrance of moisture into the space between the spindle and the barrel, and relatively hard metal balls between the cooperating races.

7. In combination, a hollow cast metal spindle having an integral enlarged head portion at its upper end, said head portion being flat on the top, an insulator post flat on the bottom seated directly upon said head, dowel pins between post and head, a bolt passing through the hollow spindle and secured to the bottom of the post, said spindle having a race at the junction of the head and the shank of the spindle, said race having a radial load surface and an axial load surface and comprising a thin hard metal disk, a barrel having an integral upper conical race and a lower race, said spindle extending within the barrel, hard metal balls between the upper barrel race and the race on the spindle, a race nut adjustable on the spindle towards and away from the lower race of the barrel, hard metal balls between said last mentioned race and the lower race of the barrel, the spindle having clamping portions at each end to which operating connections may be made to and from the spindle.
